Deuren s.c.

(57) **CLAIM**

The ornamental design for a chalk reel, as shown and described.

DESCRIPTION

FIG. 1 is a perspective view of a chalk reel showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a perspective view of an alternative embodiment of the chalk reel;

FIG. 9 is a front elevation view of FIG. 8;

FIG. 10 is a rear elevation view of FIG. 8;

FIG. 11 is a right side elevation view of FIG. 8;

FIG. 12 is a left side elevation view of FIG. 8;

FIG. 13 is a top plan view of FIG. 8; and,

FIG. 14 is a bottom plan view of FIG. 8.

The broken lines depict portions of the chalk reel in which the design is embodied that are not considered part of the claimed design.

1 Claim, 12 Drawing Sheets
